ELECTRICAL CONTROL CIRCUIT

Perry C. Smith, Moorestown, N. J., assignor to
 Radio Corporation of America, a corporation of
 Delaware

Application May 26, 1944, Serial No. 537,501

5 Claims. (Cl. 175—320)

1

This invention relates generally to electrical power control apparatus and more particularly to an improved marginal relay circuit for controlling the energization of a load device.

The invention will be explained hereinafter, by way of example, as an improvement upon the system disclosed and claimed in the copending U. S. application of Igor E. Grosdoff, Serial No. 448,254, filed June 24, 1942, now United States Patent No. 2,383,600, issued August 28, 1945, entitled "Vacuum gauge electric power supply interlock," and assigned to the same assignee as the instant application.

Heretofore, various types of pressure gauges have been utilized for indicating gas pressure or vacuum conditions within a sealed chamber. Among the most satisfactory devices for measuring the pressure at comparatively high vacuums is the well known ionization type gauge of which an extremely practical modification is known as the Phillips gauge. These devices and their applications are described in considerable detail in an article entitled "High-vacuum gauges" by F. M. Penning in Philips' Technical Review, vol. II, No. 7 for July 1937, on pages 201 to 208, inclusive.

The device disclosed in the copending application, identified heretofore, contemplates the use of a plurality of different types of vacuum gauges for indicating the gas pressure within a sealed chamber over the effective ranges of the various gauges, including an electrical circuit associated with the Phillips gauge for controlling the energization of a power circuit. Such a vacuum gauge-power interlock has great utility in the operation of an electron microscope, or similar device, in which an incandescent filament is enclosed within an evacuated container, the vacuum of which at times must be reduced to atmospheric pressure during the operation of the device. In applications of this type, serious damage to the incandescent filament may result unless some automatic means is provided for de-energizing the filament when air is introduced into the container. The circuit described may be energized, either partially or completely, from a source of alternating potential, thereby providing a simple and convenient system for accomplishing the control described heretofore.

The instant invention contemplates the use of an improved relay circuit responsive to a Phillips gauge or other control circuit, wherein the sensitivity of the relay to slight variations in energizing currents therefor is substantially increased. It is well known that conventional electromag-

2

netic relay devices which require a predetermined energizing current for actuating the armature thereof will retain said armature in the pull-down position until the energizing current is reduced substantially below the value necessary for initial attraction of the armature. Therefore, apparatus of the type described in said copending application will provide actuation of the relay armature at one predetermined vacuum condition, while the armature will not be released until the vacuum has changed to a substantially different value than that required for its initial actuation. This condition is due to residual magnetism inherent in conventional relay magnetic structures.

The purpose of the instant invention is to provide a compensating circuit, actuated by movement of the relay armature, whereby the sensitivity of the relay remains substantially constant regardless of its operating condition. Briefly, the invention comprises a novel combination of resistors and auxiliary relay contacts whereby initial attraction of the relay armature by the relay solenoid actuates a single-pole double-throw contact switch arrangement to reduce the current flow through the relay winding and in addition to compensate for the resultant difference in voltage drop across the relay winding thereby to provide substantially constant voltage across the relay actuating power circuit.

Among the objects of the invention are to provide an improved method of and means for controlling the operation of a power control relay. Another object of the invention is to provide an improved means for controlling a power circuit in response to a thermionic tube control circuit. A further object of the invention is to provide an improved vacuum gauge-thermionic tube power interlock network wherein an ionization type gauge responsive to gas pressure controls a thermionic tube having a power control relay in its output circuit and wherein the marginal operational limits of the relay are controlled by a novel compensating network. An additional object of the invention is to provide improved means for controlling the marginal operational limits of an electromagnetic relay device.

The invention will be described by reference to the accompanying drawing of which the single figure is a schematic circuit diagram of a preferred embodiment thereof.

Referring to the drawing, one terminal of a Phillips vacuum gauge 1 is connected, through a high resistance 2, to one terminal of a high voltage secondary winding 3 of a conventional

power transformer. The transformer includes a primary winding 4 which may be energized from any suitable source of alternating potential. The remaining terminal of the Philips gauge 1 is connected, through the primary winding 5 of a second transformer, to one terminal of a gas discharge tube 6, which may be of the well known neon type having a pair of electrodes. The remaining terminal of the gas discharge tube 6 is connected to one terminal of a bypass condenser 7, and to one terminal of a second resistor 8. The remaining terminal of the second resistor 8 is connected, through a sensitive D.-C. meter 9, to the remaining terminal of the capacitor 1, and to the remaining terminal of the high voltage secondary winding 3. A third resistor 10 may be connected across the extremely sensitive meter 9, if desired.

The terminals of the second transformer secondary winding 11 are connected, respectively, to the two anodes of a double-diode rectifier tube 12. The two cathodes of the diode rectifier tube 12 are connected, through a second capacitor 13, to the electrical center tap of the second transformer secondary winding 11, and to the control electrode of a thermionic amplifier tube 14. A third resistor 15 is connected in parallel with the second capacitor 13, and is also connected to the common terminal of the meter 9 and the high voltage secondary winding 3. The heater elements of the double-diode tube 12 and the amplifier tube 14 are supplied with alternating current from a low voltage secondary winding 16, provided therefor on the first transformer. If desired, connections may be provided from the low voltage secondary winding 16 to energize a power indicator such as a lamp 17.

The cathode of the amplifier tube 14 is connected through a fourth resistor 18 to the common terminal A of the meter 9 and the high voltage transformer secondary winding 3. This common terminal A is connected through a first switch 19 and a fifth resistor 20 to ground. One terminal of a voltage regulator tube 21 is connected through a second switch 22 to the cathode and the remaining terminal thereof is connected to ground. The positive terminal of a source of anode potential B is connected through a third switch 23 to one terminal C of a sixth resistor 24, the remaining terminal of which is connected to the cathode electrode of the amplifier tube 14. The negative terminal of the anode voltage supply B is grounded.

The terminal C of the sixth resistor 24 is connected, through a variable high resistor 25 and a serially-connected adjustably-tapped resistor 26, to the screen electrode of the amplifier tube 14. The winding 27 of an electromagnetic relay 28 is connected between the screen and anode electrodes of the amplifier tube. A second adjustably-tapped resistor 29 is connected across the relay winding 27.

The relay 28 includes two sets of movable contacts 30, 31 which are insulated from each other but simultaneously actuated by energization of the relay winding 27.

One terminal of the microscope electron gun or any other auxiliary load circuit 32 is connected to ground. The remaining terminal of the gun is connected, through a pressure responsive switch 33, located in the enclosed chamber 34, and through the relay contacts 30, 35, to the positive terminal of the anode potential source. It should be understood, of course, that any other

type of load circuit including a separate power source could be controlled in the same manner.

In operation, when the pressure chamber 34 is evacuated to a predetermined degree, the contacts of the pressure responsive switch 33 are closed. As the vacuum increases, the Philips gauge 1 passes an A.-C. potential or current which decreases in proportion to the decrease in gas pressure. This alternating current flows through the gas tube 6 and thereby provides illumination at both terminals of the gas discharge tube. The alternating current is bypassed by the condenser 7 around the meter 9 so that no indication is provided thereby.

As the gas pressure is reduced to the order of 10 microns, the Philips gauge becomes a rectifier, and transmits thereafter only pulsating D.-C. current. The polarity of the Philips gauge merely determines the polarity of the meter 9. This pulsating D.-C. current provides illumination of only one terminal of the gas discharge tube 6, which illumination gradually decreases as the gas pressure in the chamber is progressively reduced.

The voltages induced in the secondary winding 11 of the second transformer by the alternating or pulsating currents in its primary winding are rectified by the double-diode tube 12 to provide a positive bias on the control electrode of the amplifier tube 14, thereby energizing the relay winding 27 and opening the load circuit contacts 30, 35.

When the gas pressure in the container drops below a predetermined value, for example 5 microns, the positive potential on the control electrode of the amplifier tube 14 decreases beyond a critical value so that the normally negative grid bias potential thereon blocks the tube and de-energizes the relay 28, closing the load circuit contacts 30 and 35. It should be understood that the polarity of the diode 12 may be reversed, and reversed relay action utilized to control the load circuit energization. The resistor network comprising the resistors 18, 20 and 24 and the voltage regulator tube 21 provide, in a well known manner, a substantially constant negative control electrode bias potential for the amplifier tube 14.

If it is desired to operate the circuit entirely from alternating potentials, the power source B, the resistor 20 and the voltage regulator 21 may be disconnected, and a source of alternating potential may be connected between the terminals A and C, by means of the switches 19, 22 and 23, which may be ganged to operate simultaneously, as indicated by the dash line 36.

The second movable contact 31 of the relay 28 normally contacts a first fixed relay contact 37 which is connected to the adjustable contact 38 on the first adjustable resistor 26, thereby short-circuiting a portion of the resistor when the relay is de-energized. When the relay armature is attracted toward the relay core, the contacts 31, 37 are opened, removing said short-circuit from the portion of the resistor 26. Simultaneously the contact 31 is closed with a second fixed, normally-open, relay contact 39 which is connected to the adjustable contact 40 on the second adjustable resistor 29 which shunts the relay winding 27. Closing of the contacts 31, 39 short-circuits a portion of the resistor 29, thereby reducing the voltage drop across the relay winding 27, and reducing the magnetic attraction between the relay core and its armature.

By adjustment of the taps 48 and 38 on the adjustable tapped resistors 29, 26, respectively, the relay may be caused to open and close the load contacts 30, 35 in response to very slight variations in the voltage derived from the Phillips gauge 1 and applied to the control electrode of the amplifier tube 14. Also, although the voltage drop across the relay winding 27 is varied by operation of the relay contacts 31, 39, the effective voltage applied to the amplifier tube anode may be maintained substantially constant due to the compensating action of the relay contacts 31, 37 connected across the portion of the series resistor 26. This latter feature is particularly desirable when pentode or constant current type tubes are not employed for the relay actuating amplifier.

The variable high resistor 25 may be adjusted to provide coarse control of the relay operating range prior to the fine adjustment thereof by means of the adjustable contacts and the adjustable resistors 26 and 29.

Thus the invention disclosed comprises an improved method of and means for controlling the sensitivity of an electromagnetic power control relay, wherein compensating resistors, controlled by contacts on said relay, permit the marginal limits of the relay actuating currents to be adjusted over a predetermined wide or narrow range, and wherein said compensating elements may be adjusted to provide substantially constant load upon the relay energizing source. It should be understood that any known type of relay control and energizing system may be employed, and that the invention is not necessarily limited to vacuum tube relays of the general type described heretofore.

I claim as my invention:

1. An electrical marginal control circuit including an electromagnetic relay device having a solenoid winding and means for controlling a load device, connecting means for a source of current for selectively energizing said winding to actuate said load controlling means, a first resistor connected to said winding, a second resistor connected to said winding, single pole-double throw contact means on said device operable in response to said selective energization of said winding and connected to said resistors for selectively adjusting the effective resistance of said first resistor upon energization of said winding for adjusting said energizing current to control the marginal operation of said relay device and for adjusting the effective resistance of said second resistor upon deenergization of said winding for simultaneously maintaining substantially constant the loading of said current source.

2. An electrical marginal control circuit including an electromagnetic relay device having a solenoid winding and means for controlling a load device, connecting means for a source of current for selectively energizing said winding to actuate said load controlling means, a first resistor shunting said winding and having an intermediate connection thereon, a second resistor having an intermediate tap and serially connected with said winding, single pole-double throw contact means on said device operable in response to said selective energization of said winding and connected to said intermediate taps on said resistors for selectively short-circuiting a portion of said first resistor upon energization of said winding for adjusting said energizing current to control the marginal operation of said relay device and for short-circuiting a portion

of said second resistor upon deenergization of said winding for simultaneously maintaining substantially constant the loading of said current source.

3. An electrical marginal control circuit including an electromagnetic relay device having a solenoid winding and means for controlling a load device, connecting means for a source of current for selectively energizing said winding to actuate said load controlling means, a first impedance device connected to said winding and having an intermediate connection thereon, first contact means on said device operable in response to said selective energization of said winding and connected to said intermediate tap on said impedance device for selectively adjusting the portion of said impedance device connected to said winding upon energization of said winding for adjusting said energizing current to control the marginal operation of said relay device, a second impedance device connected with said winding and having an intermediate connection thereon, and second contact means on said device operable in response to said winding energizing current and connected to said intermediate tap on said second impedance device for adjusting the impedance of said second impedance device upon deenergization of said winding for simultaneously maintaining substantially constant the loading of said current source.

4. An electrical marginal control circuit including an electromagnetic relay device having a solenoid winding and means for controlling a load device, connecting means for a source of current for selectively energizing said winding to actuate said load controlling means, a resistor shunting said winding and having an intermediate connection thereon, first contact means on said device operable in response to said selective energization of said winding and connected to said intermediate tap on said resistor for selectively short-circuiting a portion of said resistor upon energization of said winding for adjusting said energizing current to control the marginal operation of said relay device, a second resistor serially connected with said winding and having an intermediate connection thereon, and second contact means on said device operable in response to said winding energizing current and connected to said intermediate tap on said second resistor for short-circuiting a portion of said second resistor upon deenergization of said winding for simultaneously maintaining substantially constant the loading of said current source.

5. An electrical marginal control circuit including an electromagnetic relay device having a solenoid winding and means for controlling a load device, connecting means for a source of current for selectively energizing said winding to actuate said load controlling means, a resistor shunting said winding and having an intermediate connection thereon, a movable contact means on said device operable in response to said selective energization of said winding, a first fixed contact operatively disposed adjacent said movable contact and connected to said intermediate tap on said resistor for selectively short-circuiting a portion of said resistor upon energization of said winding for adjusting said energizing current to control the marginal operating current limits of said relay device, a second resistor serially connected with said winding and having an intermediate connection thereon, and second fixed contact means on said device operatively disposed adjacent said movable

contact and connected to said intermediate tap on said second resistor for short-circuiting a portion of said second resistor upon deenergization of said winding for simultaneously maintaining substantially constant the loading of said current source.
